UNITED STATES PATENT OFFICE.

ALBERT WANNER, JR., OF HOBOKEN, NEW JERSEY.

DESIGN FOR A FURNITURE-BRACE.

40,572.

Specification for Design.

Patented Mar. 8, 1910.

Application filed February 4, 1909. Serial No. 476,178. Term of patent 14 years.

To all whom it may concern:

Be it known that I, ALBERT WANNER, JR., a citizen of the United States, residing in Hoboken, Hudson county, New Jersey, have invented a new, original, and ornamental Design for Furniture-Braces, of which the following is a specification, reference being had to the accompanying drawing, forming part hereof.

The drawing shows, Figure 1, a view in front elevation of the brace; Fig. 2, a view in side elevation; and, Fig. 3, a plan.

As seen from the side (Fig. 2) the brace comprises the vertical parts *a* and *b* projecting in opposite directions from the ends of an intermediate part *c*, parts *a* and *b* standing at right angles to part *c*; further, parts *b* and *c* are connected by a web *d*.

Viewed in front elevation (Fig. 1) part *a*

converges upwardly, has its upper end rounded, and is formed with a vertically elongated opening *e*. The under side of part *c*, in front elevation, appears as a convex curve *f*. The part *b* appears in front elevation as substantially a rectangle and has a hole *g* below the web *d*.

Viewed in plan (Fig. 3), part *a* appears flat, part *c* converges rearwardly, except at its rear end, where its sides are substantially parallel, and part *b* has the part-cylindrical groove *h*, and a rounded front face.

I claim:

The ornamental design for a furniture brace, as shown and described.

ALBERT WANNER, JR.
